UNITED STATES PATENT OFFICE.

RUFUS M. BRUNDIGE, OF NEW YORK, N. Y.

DESIGN FOR DISHES.

Specification forming part of Design No. **11,411**, dated September 9, 1879; application filed June 17, 1879.
[Term of patent 7 years.]

To all whom it may concern:

Be it known that I, R. M. BRUNDIGE, of New York city, in the State of New York, have invented a Design for a Set of Dishes, of which the following is a specification.

Figure 1 of drawing is a perspective, and Fig. 2 a side, view.

The dishes are intended for ice-cream, jellies, or preserves, and provided with handles.

The design consists in the peculiar configuration hereinafter described.

A represents a bottom, which may be plain or ornamental. At an obtuse angle to this rises an angular or arc-shaped front portion, B, from the ends of which extend the straight sides C C, which converge until they form a

junction with the handle D, that rises obliquely above the dish.

Having thus described all that is necessary to a full understanding of my design, what I claim as new and of my invention is—

A design for a set of ice-cream, jelly, or preserve dishes, that consists in combining with the bottom of each dish and the front B converging straight sides C C and the handle D, all rising from the bottom A at an oblique angle, and connecting with one another, as shown and described.

RUFUS M. BRUNDIGE.
